UNITED STATES PATENT OFFICE.

ANTHONY T. MOORE, OF NEW HAVEN, CONNECTICUT, ASSIGNOR TO PERRYS INCORPORATED, OF WATERBURY, CONNECTICUT, A CORPORATION.

LAUNDRY-CLASSIFYING TABLE.

Application filed November 18, 1927. Serial No. 234,092.

This invention relates to improvement in laundry classifying tables, the object being to provide a table conveniently operated and with which the possibility of mixing two lots is avoided, and the invention consists in the construction as hereinafter described and particularly recited in the claims.

In the accompanying drawings:

Fig. 1 is a perspective view of a laundry classifying table constructed in accordance with my invention and shown in position ready for sorting laundry work;

Fig. 2 is a similar view with the hopper in its depressed position;

Fig. 3 is a broken plan view showing the lower bar engaged with one of the inner side-walls of one of the tables and showing an identification-pin-tag bracket mounted thereon; and

Fig. 4 is a similar view with the lower bar turned, showing the identification-pin-tag bracket in line with the inner side-wall of one of the tables, so as to be knocked off thereby when the hopper is lowered.

In carrying out my invention, I employ two sorting-tables 5 and 6 suitably supported by front legs 7, rear legs 8 and intermediate legs 9, the two tables being connected at the rear by a brace 10. The inner side-walls 11 and 12 of the tables are formed with clearance-notches 13 for the purpose as will hereinafter appear. Between the tables is a hopper 14 provided at its sides with handle-bars 15 and 16 having handle-ends 17 hinged thereto. The said handle-bars 15 and 16 are pivotally connected with the side-walls 11 and 12 of the tables, and pivoted to the under-side of the hopper is a locking-bar 18, longer than the width of the hopper, so that, when turned, its ends will engage with the notches 13 in those walls, whereby the hopper will be held in an elevated position. Connected with the locking-bar is a forwardly-projecting lever 19 by which the locking-bar may be turned upon its pivot. The outer side-walls 20 and 21 project beyond the forward edges of the tables 5 and 6, and the handle-bars 15 and 16 project beyond the tables, in line with the side-walls 20 and 21, so that the handle-ends 17 may be turned outward and be interlocked with the front legs 7 by spring-latches 22. The forward ends of the side-walls 20 and 21, the forward ends 23 of the tables, the forward ends of the handle-bars 15 and 16,

and the handle-ends 17 are provided with upwardly-projecting pins 24, from which laundry-bags 25 may be suspended. On the locking-bar 18, at the right, is a post 26 having inclined pins 27 on its forward side upon which a bracket 28 may be supported, this bracket being adapted to carry identification-pin-tags 29 of usual construction, and, if desired, in the top of the post may be a pin 30 upon which a ticket may be filed.

Before beginning operations, the handle-ends 17 will be disconnected from the front legs 7 and turned into line with the handle-bars 15 and 16; then, while one of the handle-ends is held with one hand, the lever 19 is pressed rearward with the other hand, so as to turn the locking-bar 18 out of engagement with the side-walls 11 and 12, so that the hopper may be tilted downward, as shown in Fig. 2 of the drawings. A lot of laundry is then dumped into the hopper, and in this position it is so low that this can be conveniently done. Downward pressure is then imposed upon the handle-ends 17 and the hopper lifted, so that a forward movement of the lever 19 will turn the locking-bar 18 into engagement with the flanges 11 and 12 and so firmly support the hopper. The handle-ends 17 are then turned outward and interlocked with the front legs 7 and bags 25 supported upon the pins 24. A bracket 28 will then be suspended upon the pins 27 and the sorting commenced, white goods being placed on one table and colored goods on the other.

When the sorting takes place, the bags are detached and the identification-pin-tags removed from the bracket and used to close the mouth of the bags, and if the amount of material on any one table is more than enough to fill one bag, that bag will be removed and replaced by another, the same number identification-pin-tags being used on all bags of a single lot. If a slip has been employed, it may be placed upon the file-pin 30.

When the sorting operation of one lot is completed and it has been properly bagged, the handle-ends 17 will be released from the front-legs 7 and turned into line with the handle-bars 15 and 16 and pressed down slightly, so as to raise the locking-bar 18 just above the lower face of the notches 13 in the side-walls 11 and 12, so that this

bar may be readily turned by an inward thrust upon the lever 19, and then the hopper will be permitted to be turned to its "down" position, and in case the operator 5 has failed to remove the bracket 28 from the pins 27 on the downward movement of the hopper, this bracket will strike the side-wall 11 and be lifted off from the pins 27 and allowed to fall on the floor or into a receptacle, but in any case, it cannot remain 10 upon the post 26, so that identification-pintags used on one lot cannot be used on another lot, as the operator must place a new bracket upon the pins before closing any 15 bags of a certain lot.

With this construction, the hopper is presented in convenient position and so low that laundry may be readily dumped into it when in its "down" position, and when in 20 its raised position is in a convenient place for an operator.

I claim:

1. A laundry classifying table, comprising 25 two table parts with supports therefor, a hopper pivotally mounted between said tables near the forward ends thereof, and a locking-bar pivoted to the underside of said hopper near its rear end and adapted to be turned into engagement with the inner sides 30 of said tables when the hopper is in its raised position, said hopper provided with handles by which it may be raised or lowered.

2. A laundry classifying table, comprising 35 two tables suitably supported, a hopper provided with handle-bars pivotally connected with said tables, said handle-bars having handle-ends hinged thereto, the inner side-walls of the tables having notches, 40 a locking-bar pivoted to the under-side of

the hopper and adapted to enter the notches in the side-walls of the tables, and a lever connected with said locking-bar and projecting forwardly therefrom.

3. A laundry classifying table, comprising two tables arranged side by side and connected together at the rear, a hopper pivotally connected between said tables, means for turning the locking-bar into engagement with the sides of said tables, the outer sides of the said tables projecting beyond the inner sides thereof, handle-bars connected with said hopper and projecting outward in line with the outer side-walls of the tables, handle-ends hinged to said handle-bars and adapted to be turned outward into engagement with the forward ends of the outer sides of the tables, and the said forward sides of the tables, forward ends of the tables, forward ends of the side-bars and 60 the handle-bars provided with upwardly-projecting pins.

4. A laundry classifying table, comprising 65 two tables suitably supported, a hopper provided with handle-bars pivotally connected with said tables, said handle-bars having handle-ends hinged thereto, the inner side-walls of the tables having notches, a locking-bar pivoted to the under-side of the hopper and adapted to enter the notches 70 in the side-walls of the tables, a lever connected with said locking-bar and projecting forwardly therefrom, the said locking-bar provided at one side with an upwardly-projecting post, and pins projecting upward 75 from the forward face of said post for the support of an identification-pin-tag bracket.

In testimony whereof, I have signed this specification.

ANTHONY T. MOORE.
